LOCK

Rollo Marple, Jackson, Mich., assignor to Hancock Manufacturing Company, Jackson, Mich., a corporation of Michigan

Original application October 20, 1938, Serial No. 235,982, now Patent No. 2,301,221, dated November 10, 1942. Divided and this application October 5, 1942, Serial No. 460,772

2 Claims. (Cl. 292—354)

The present invention relates to latching devices for closures, and in particular provides an improved latch construction for vehicle doors.

This application is a division of applicant's copending application, Serial No. 235,982, filed October 20, 1938, now Patent No. 2,301,221, granted November 10, 1942.

The principal objects of the present invention are to provide an improved latch of the above generally indicated character, particularly adapted for, but not limited to, use in connection with vehicle doors, characterized as being simple in construction, economical of manufacture, and extremely durable and efficient in operation; to provide a latch of the rotary bolt type, embodying an improved actuating connection between the inside and outside door operating handles and the bolt actuating means; to provide a latch of the rotary bolt type embodying improved means operable from within the vehicle for locking the inside and outside handles against actuation; to provide improved means actuated by the bolt for releasing the locking means; to provide a door latch embodying improved means for supporting an actuating spindle in relation to the latch casing; to provide a door latch embodying means for wedgingly retaining the spindle against rattling, and including spring means for urging the handle to a predetermined position; and to generally improve the construction and operation of vehicle door latches.

With the above as well as other objects in view, which appear in the following description and in the appended claims, a preferred but illustrative embodiment of the invention is shown in the accompanying drawings, throughout the several views of which corresponding reference characters are used to designate corresponding parts and in which:

Figure 1 is a view in elevation, illustrating the application of the invention to automobile doors;

Fig. 2 is a view in transverse section, taken along the line 2—2 of Fig. 1;

Fig. 3 is a view in vertical section, taken along the line 3—3 of Fig. 2;

Fig. 4 is a view in elevation, taken along the line 4—4 of Fig. 2;

Figs. 5 and 6 are comparative views, Fig. 5 being a view taken along the line 5—5 of Fig. 4;

Fig. 7 is a view in vertical section, taken along the line 7—7 of Fig. 4;

Fig. 8 is a detail view in section, taken along the line 8—8 of Fig. 6;

Fig. 9 is a detailed fragmentary view, taken along the line 9—9 of Fig. 8; and

Fig. 10 is a comparative view, illustrating the parts shown in Fig. 4, but with the locking cams in the retracted position thereof.

The improved latch, which is secured within the door 20 of the associated vehicle, comprises generally a casing member 22; a rotary bolt 24; a plurality of cams designated collectively as 26, for holding the bolt against rotation in a door-opening direction; an outside operated rollback means, designated as a whole as 28, for releasing the cams 26 and the bolt 24 in response to movement of the conventional outside handle; and a retracting member 30, which may be connected to the conventional inside door handle or the like 15 (not shown), to release the cams 26 from operative engagement with the bolt. The keeper 32, which is described in more detail below, is suitably secured to the door pillar 24, as by means of bracket 36.

20 The bolt 24 is rotatably journaled in the latch casing upon a pin or trunnion 40. One end of the pin 40 is supported in the flange 42 of a bracket 44, which is suitably secured, as by welding, to the flange 46 of the previously identified casing 22. The other end of the pin 40 is supported in a supplemental casing member 48, which is suitably secured to the inner face of the flange 46. The bolt 24 is formed to provide a keeper-engaging portion 50, which projects externally of the lock casing 22 for cooperation with the keeper 32; an inner or cam-engaging portion 52; and a separating fin or vane 54, which is somewhat larger in diameter than the portions 50 and 52, and serves to substantially close the opening which is provided in the flange 46 of the casing 22 to accommodate the bolt. The lower half of the outwardly projecting portion 50 of the bolt 24 is substantially enclosed by the previously mentioned bracket 44, which is given a substantially semi-cylindrical form for this purpose.

As most clearly appears in Figs. 3 and 7, the outer portion 50 of the bolt 24 is formed to provide a plurality of radially extending equiangularly spaced keeper-engaging teeth or projections 50a, any one of which is effective, as described hereinafter, to cooperate with the safety catch 60 associated with the keeper, or the keeper portion 62, to hold the door in either the partially closed or safety position, or in the fully closed position, respectively. It will be appreciated that the angular spacing between the projections or teeth 50a relative to the spacing between the safety catch 60 and the keeper portion 62, is such that the bolt 24 can roll over or cross the keeper

in a manner similar to the cooperation between a gear and a rack.

As most clearly appears in Figs. 4, 7 and 10, the inner portion 52 of the bolt 24 is formed to provide a number of dog-engaging teeth or projections 52a, the number and angular spacing between which corresponds to the number and angular spacing of the keeper engaging teeth 50a. The teeth 52a, however, are angularly displaced from the teeth 50a. This relation results in reducing the space requirements for the lock, since the positioning of the cam can thus be determined independently of the rotative position of the teeth 50a. Each tooth 52a is formed to provide a generally radially extending cam-engaging portion 64 and a locking portion 66, the purpose whereof is described hereinafter.

The cams 26 are provided to cooperate with the latching portion 66 of the bolt 24 to hold the bolt 24 against rotation in a clockwise, or door-opening direction, as viewed in Figs. 3, 4 and 10. It is preferred to utilize a plurality of such cams of progressively increasing length, to provide a take-up action for the latch, as hereinafter described. In the present instance, three cams are illustrated, although a smaller or larger number may be utilized, if desired.

The three cams, designated as a whole at 26, are rotatably supported in the lock casing upon a pin or trunnion 70, which extends parallel to, but spaced from, the previously mentioned bolt supporting pin 40. The outer end of the pin 70 is supported in a member 72, the inner flanges 74 whereof are secured to the inner face of the casing flange 46, and the outwardly extending body portion whereof serves, as most clearly appears in Figs. 3 and 7, as a dovetail member. The inner end of the pin 70 is supported in the previously mentioned supplemental casing member 48. Each of the three cams, which are individually designated as 76, 78 and 80, includes a downwardly extending body, which terminates in a laterally offset foot. The cam 76 is slightly longer than the cam 78, and the cam 78 in turn is slightly longer than the cam 80. Each of the cams 76, 78 and 80 is provided with a biasing spring 82 individual thereto. One end of each spring is secured between a pair of lugs 84, which are inwardly struck from the casing flange 46, and the free end of each spring 82 bears against the edge of the associated cam and so continuously urges it in a counterclockwise or locking direction, as viewed in Figs. 4 and 10.

The outside rollback, designated as a whole as 28, embodies an improved arrangement which is susceptible of general application, but finds particular utility when utilized in connection with a lock of the present character. In the illustrated instance, the outside rollback 28 comprises a pair of rollback members 27 and 29. The rollback member 29 is provided with an axially extending boss 31, which is received and rotatably journaled in a corresponding opening provided therefor in the lock casing 22. The companion rollback member 27 is provided with a corresponding axially extending boss 33, which seats within a complementary recess formed in the face of the companion rollback member 29. In accordance with the arrangement disclosed and claimed in Patent No. 1,895,893, granted to Raymond G. Moore, the rollback members 27 and 29 are provided with squared openings therein, which are slightly angularly offset from each other, and which are dimensioned to relatively freely receive the squared spindle 88 associated with the outside

operating handle. With this relation, when the spindle 88 is inserted through the rollback members 27 and 29, they are slightly angularly offset from each other as clearly appears in Figs. 5 and 6. In the present instance, a coil spring 35 surrounds the spindle 88, and one end 37 thereof is laterally turned and passed through registering and correspondingly positioned openings such as 39 provided therefor in each of the rollback members 27 and 29, as most clearly appears in Figs. 8 and 9. The turned portion 37 thus urges the members 27 and 29 into alignment with each other. The other end 39 of the spring 35 extends downwardly and, as most clearly appears in Fig. 4, is hooked into an opening provided therefor in the supplemental casing member 48. The spring 35 thus continuously urges the rollback members 27 and 29 in a counterclockwise direction as viewed in Figs. 5 and 6, and, except when these members are actuated by rotation of the spindle 88, holds the inner rollback member 29 in abutting relation to the upper wall of the just-mentioned supplemental casing member 48. A movement of the rollback 28 winds up the spring 35, and thus renders it effective to apply a substantial restoring force thereto. At the same time, the spring 35 urges the other rollback element 27 in the same direction, tending to bring the two elements into alignment with each other, which action, however, tends to angularly offset the squared openings therein with respect to each other, and so wedges the spindle 88 between the two rollback members 27 and 29. This action, as well as serving to retain the outside handle in the normal elevated position shown in Fig. 1, also effectively prevents rattling thereof.

The rollback members 27 and 29 and the spring 35 are held in the assembled relation shown in Fig. 8 by a supplemental casing member 41 which is secured to the base 86 of the case plate. The casing member has an opening therethrough to accommodate the spindle 88, and fingers 43, which project radially inwardly from the opening, overlie the spring 35.

The outer end of the rollback member 29 normally bears against a laterally turned foot 90 associated with the previously mentioned retracting member 30, and clockwise rotation of the outside rollback mechanism, as influenced by the spindle 88, causes a counterclockwise rotation of such member 30, as viewed in Figs. 5 and 6, which in turn causes a retracting movement of the previously mentioned locking cams 26, as hereinabove described.

The member 30 is pivotally supported upon the base 86 of the casing 22, by means of a pin 100. One end of the pin 100 is mounted in the base 86 of the casing 22, and the other end thereof is supported by the previously mentioned supplemental casing member 41. One end 102 of the member 30 is adapted for connection to conventional link mechanism (not shown) which may extend to an inside door-operating handle. The member 30 is also provided with a foot 104, which normally bears against a foot 94 associated with the cam 80. In order to render the cams 76 and 78 responsive to the movement of the cam 80, as influenced by the just mentioned foot 94 provided thereon, the cam 80 is provided with a laterally turned portion 106, which extends around and behind the rear edges of the cams 76 and 78. With the just mentioned arrangement, it will be appreciated that clockwise rotation of the member 30, as influenced either by the outside rollback 28, or by suitable actuation of the inside handle (not

shown), causes the foot 104 on the member 30 to bear downwardly upon and cause downward movement of the foot 94, which action in turn causes all of the cams 76, 78 and 80 to move in a clockwise direction, from the locking position shown in Fig. 4, to the unlatched position shown in Fig. 10. This movement of the cams releases them from the bolt 24, and permits the latter to be rotated in a clockwise or door-opening direction. Upon releasing either the outside rollback 28, or the inside handle (not shown), however, the spring 96 associated with the member 30 becomes effective to rotate the latter in a clockwise direction, as viewed in Figs. 5 and 6, to the normal latched position thereof, shown in Fig. 6. This action renders the springs 82 associated with the cams effective to urge them in a counterclockwise direction, as viewed in Figs. 3, 4 and 10, to the normal latching position, shown in Fig. 4.

Referring particularly to Fig. 3, the keeper 32 comprises a body, which may be and preferably is formed as a relatively heavy metal stamping, and which is formed to define the previously mentioned bolt-engaging surface 62. The previously mentioned safety catch 60 is and may be formed of a die casting or the like, and is pivotally supported by a pin 114, which extends between and is supported in the opposite side walls of the keeper 32. A spring 116 is connected between the catch 60 and the keeper body, and continuously urges the safety catch 60 to the active position shown in Fig. 3. It will be noted that the otherwise continuous body of the keeper 32 is cut away, as indicated at 118, to afford a slot or opening through which the safety catch 60 may move from the active position shown in Fig. 3, to a retired position. It will also be noted that the back of the safety catch 60 abuts the portion 119 of the body of the keeper 32, so that such portion 119 forms a limit stop to the rotation thereof under the influence of the spring 116.

Also, as clearly appears in Fig. 3, when the door is in a closed position, the keeper 32 is in a position between the rotary bolt 24 and the previously mentioned dovetail member 72. The upper surface of the keeper 32, as well as the under surface of the dovetail member 72, are downwardly inclined in the direction of the door-closing movement. With this relation, the dovetail member tends to serve as a stop to the movement of the keeper 32 in the leftward or door-closing direction, as influenced by the bolt 24. The members 24, 32 and 72, accordingly, function in accordance with the functioning of the usual separately formed dovetails usually associated with locks of the conventional slidable bolt type, and permits such separate dovetail structures to be dispensed with.

In accordance with the present invention, locking means are provided for the inside and outside actuating mechanisms, which may be operated between a retracted position permitting free movement of the actuating mechanisms, and a locking position, in which both the inside handle and the outside handle are rendered ineffective. In the illustrated instance, this locking mechanism comprises an abutment, constituted by a roller member 130, the reduced ends whereof are disposed to ride in registering slots such as 132 formed in the base 86 of the casing 22 and in the casing member 41. In the retracted position of the locking roller 130, shown in Fig. 6, it is positioned out of the path of movement of the member 30, and consequently does not interfere with the normal movement thereof. When, however,

the roller 130 is moved downwardly to the locking position shown in Fig. 5, it occupies a position in blocking relation to the extension 134 of the inside retracting member 30, and positively prevents rotation thereof in a counterclockwise or door-unlocking direction.

In the illustrated instance, the roller 130 is arranged for control by a rod 136, which may extend upwardly from the lock body within the vehicle door 20, and terminates in a button 138 which projects slightly through the garnish mould 20a associated with the door 20. The link 136 is normally retained in either the locking or the unlocking position, by means of a spring 140, which is suitably secured to the flange 86 of the casing 22, and the free end 142 whereof is angularly formed. With this relation, it will be appreciated that the spring 140 is effective to yieldingly hold the roller 130 in either the locking or the unlocking position.

In utilizing an inside locking device, effective to prevent actuation of either the inside or the outside handles, it is preferred to arrange the locking means so a retracting movement of the bolt 24 releases it. This expedient overcomes any difficulty which might otherwise result from the locking button 138 being moved to locking position while the door is open, and the door thereafter closed. Such a closing action under these circumstances would, of course, prevent access to the car through the door in question. In the present instance, the just mentioned release is effected by an additional pivotally mounted link 144, which is carried by the previously mentioned pin 100. The link 144 is provided with a nose 146 which is positioned in the path of movement of the locking roller 130, and an additional foot 148, which is positioned in the path of the foot 94 associated with the locking cams 76, 78 and 80. With the parts occupying the positions shown in Fig. 5, it will be recalled that the retracting member 30 is locked against a retracting movement. The cam foot 94 is, however, free to move downwardly through a normal unlocking movement. Such a movement caused, for example, by closing the door 20, enables the foot 94 to cam the foot 148 downwardly, swinging the nose 146 in a counterclockwise direction.

The counterclockwise movement of the nose 146 cams the roller 130 upwardly far enough to bring it past the angular portion of the spring 140, thus rendering this spring effective to force the locking roller 130 to its fully elevated position, shown in Fig. 6. The downward movement of the cam foot 94 as influenced by a closing movement of the door, brings the link 144 to a position intermediate that shown in Figs. 5 and 6, in which the cam nose 146 thereof extends across the path of the roller 130 but does not block downward movement thereof. Accordingly, following the closure of the door as just described, the roller 130 may again be forced downwardly to the locking position, by operation of the inside button 138.

The lowering movement of the cam foot 94, as influenced by a closing movement of the door, as above described, is, of course, just sufficient to swing the cams 26 (Fig. 10) far enough to permit the bolt to rotate past the cams. On the other hand, when the outside or inside handle is actuated, as previously described, to actuate the member 30 and in turn retract the cams 26, a somewhat greater downward movement of the cam foot 94 results, since under these conditions it is desired to swing the cams 26 to a position

entirely out of engageable relation with the teeth 52a of the inner bolt portion, thus rendering the bolt entirely freely rotatable. The additional downward movement of the foot 94 thus occasioned, swings the auxiliary link 144 somewhat further in a counterclockwise direction, and brings it to a position in full blocking relation to the roller 130. In order to restore the auxiliary link 144 to the intermediate position discussed above, in which the nose 146 thereof extends across the path of travel of the roller 130 but does not prevent downward movement thereof, the link 144 is provided with a nose portion 150, which is engageable by an offset portion 152 5 formed on the retracting member 30. Accordingly, the retracting member 30, which resumes the position shown in Fig. 5 upon release of either the inside or the outside handle, as influenced by the spring 96, is effective to return the auxiliary link 144 to the above mentioned intermediate position.

It is preferred to provide an externally operated key control mechanism to render the outside handle ineffective. For this purpose, a slide 160 is provided, which is guided on the base 86 of the case plate, and which is provided with a nose 162 for cooperation with a portion 164 of the nose 162 for cooperation with a portion 164 of the retracting member 30. When the slide 160 is in the raised position, shown in Fig. 5, the nose 162 lies in blocking relation to the portion 164 and thus prevents an unlatching movement of the member 30. The slide 160 is controlled by a key operated cam 166, which may be rotated, by suitable key mechanism from the exterior of the door, from the elevated position, shown in Fig. 5, to the retracted position, shown in Fig. 6. In the latter position, the cam 166 holds the slide 160 in the lower position in which the nose 162 thereof is out of range of the portion 164.

Considering the operation as a whole of the above described construction, the parts are shown in Figs. 2, 3, 4, 5 and 7 in positions occupied thereby when the door is in a fully or tightly closed position and with the locking roller 130 in locked position. Under these circumstances, the upper tooth 50a of the outer portion 50 of the rotary bolt 24 bears solidly against the cooperating surface 62 of the keeper 32, forcibly wedging the latter between the bolt 24 and the dovetail member 12. At the same time, the foot of the longest dog 76 bears solidly against the upper substantially horizontally disposed locking surface 66 associated with the inner portion of the bolt 24. Cam 76 is thus effective to entirely prevent any clockwise rotation of bolt 24, so that the door is positively held in the just-mentioned fully or tightly closed position. To condition for normal operation, the locking roller 130 may be moved to the upper position, shown in Fig. 6, and the key slide 160 may be moved to the lower position, shown in the same figure.

To open the door, either the outside rollback 28, or the means associated with the inside handle (not shown) may be actuated, to rotate the member 30 in a counterclockwise direction from the position shown in Fig. 5 to the position shown in Fig. 6. It will be understood that in the event the actuation of the member 30 is effected by the means of the inside handle (not shown) the outside rollback 28 remains in the retracted position shown in Fig. 5, in which position it is retained by the spring 35. The counterclockwise rotation of the member 30, forces the shoulder 94 associated with the cam 80 downwardly, there- 10 by rotating all three of the cams 76, 78 and 80

in a clockwise direction, as viewed in Figs. 3, 4 and 6, from the locking position shown in Fig. 4, to the fully unlocked position. This rotation of the cams, which takes place in opposition to the forces of their associated biasing springs 82, moves the feet thereof out of range of the teeth 52a of the inner portion of the rotary bolt 24, thereby permitting the latter to be freely rotated in a clockwise or door-opening direction, in response to the movement thereof over the keeper surface 62 and the safety catch 60.

Upon release of the inside member 30, either as a consequence of the release of the outside rollback 28, or as a consequence of the release of the inside handle (not shown), which may be expected to occur shortly after the bolt 24 passes beyond the keeper safety catch 60, the springs 82 again become effective to return the cams 26 to the positions shown in Fig. 4, in which they are effective to hold the bolt in the corresponding illustrated position. The return movement of the cams also causes the foot 94 to move upwardly to the position shown in Fig. 5 and enables the member 30 to resume its normal position shown in the same figure.

During a door closing movement, the bolt 24 moves to the right relative to the keeper 32, as viewed in Fig. 3. As the door approaches a partially closed position, corresponding to the conventional safety position, the safety catch 60 engages the right-hand face of the upper tooth 50a associated with the bolt 24. Continued door-closing movement causes the catch 60 to apply a rotative force to the bolt 24. The springs 82, however, associated with the cams, are stronger than the spring 116 associated with the safety catch 60, so that no rotative movement of the bolt occurs. Instead, the safety catch 60 rotates in a counterclockwise direction relative to the keeper 32 to a retired position, in which the tooth may be moved past the keeper 32. As soon as the end of the safety catch 60 is passed by the upper bolt tooth, the spring 116 associated therewith is rendered effective to cause the safety catch to return to the active position, shown in Fig. 3, in which it is effective to cooperate with the left-hand face of the upper bolt tooth 50a and positively prevent the door from again being fully opened without again actuating the cams, designated collectively as 26, to release the bolt 24.

If the door closing movement is continued beyond the safety position, just described, the sloping face 120 of the keeper 32 is brought into engagement with the right-hand face of the upper bolt tooth 50a, and applies a positive rotative force to the bolt 24. Due to the fact that the bolt holding effect of the cams results from the cooperation between the teeth thereof and the bolt faces and not from the strength of the biasing springs 82, it is possible to utilize springs 82, which are relatively weak.

Accordingly, a minimum door-closing force is required to render the keeper face 120 effective to rotate the bolt 24 in a counterclockwise direction, as viewed in Figs. 3, 4 and 6. During such movement, a leading face 64 of an inner bolt tooth 52a bears against the rear edges of the cams and turns these cams to the position shown in Fig. 4 to positions corresponding to those shown in Fig. 10.

When the door reaches a substantially closed position, the just-mentioned inner bolt tooth face 64 passes beyond the heel of the shorter cam 80, permitting the latter to ride up over the rounded ends of the cam engaging bolt face 66. As soon

as this action takes place, the spring 82 associated with the cam 80 becomes effective to rotate the latter in a counterclockwise direction, as viewed in Fig. 10, and forcibly continues the rotation of the bolt 24 in a counterclockwise or door-closing direction. At slightly spaced stages in the continued door-closing movement, the bolt face 64 successively passes beyond the heels of the cams 78 and 76, rendering the springs 82 associated with these cams successively effective to continue the counterclockwise or door-closing rotation of the bolt 24. The cams 76 and 78 may be expected, in the fully closed position of the door, to occupy the full blocking position described with reference to cam 80.

Reviewing the locking relations, it is noted that the inside-locking means comprising the roller 130 may be manually moved at any time from the lower locked position, shown in Fig. 5, to the upper unlocked position, shown in Fig. 6, and that this mechanism is yieldably retained by the spring 140 in either of these two positions. When in the lower position, the roller 130 blocks rotation of the retracting member 30 and so renders the outside rollback mechanism ineffective. The inside handle mechanism (not shown), which is disposed to be connected to the part 102 of the retracting member 30 is correspondingly rendered ineffective. A closing movement of the door, which causes a retraction of the holding cams 26 and a corresponding downward movement of the foot 94 (Fig. 5) serves to rotate the auxiliary link 144 and release the locking mechanism, if previously set in locking position to the unlocked position, shown in Fig. 6. The outside locking mechanism comprising the slide 160 is selectively adjustable to lock the retracting member 30

against movement, so that the door may be positively locked from the outside thereof.

From the foregoing, it will be appreciated that the present invention provides an extremely effective door lock structure, which is simple and economical of manufacture, and which is exceptionally efficient and satisfactory in operation. It will also be appreciated that the specifically described embodiment is illustrative and that various modifications in the form, number and arrangement of the described parts may be made within the spirit and scope of the invention.

What is claimed is:

1. In control means for a latch having an anchor, the combination of a rotatable spindle, rollback means comprising a pair of rollback elements on said spindle having openings through which the spindle passes so as to form loose but driving connections therebetween, rotation of said spindle from a normal position serving through the consequent movement of said rollback means to control said latch, and spring means including means coupled between the rollback means and said anchor for continuously urging said spindle to a normal position and further including means coupled between the respective said rollback elements effective during rotation of the spindle to act between said rollback elements and bias them relatively to each other in such direction as to cause them to bind on said spindle.
2. Structure according to claim 1, wherein the spring means constitutes a single spring having portions coupled between the rollback means and said anchoring means.

ROLLO MARPLE.
